St John & Brown

Street Sweeper

No 13,830.

Patented Nov 20, 1855.

UNITED STATES PATENT OFFICE.

M. W. ST. JOHN AND I. BROWN, OF LEONARDSVILLE, NEW YORK.

STREET-SWEEPING MACHINE.

Specification of Letters Patent No. 13,830, dated November 20, 1855.

To all whom it may concern:

Be it known that we, M. W. ST. JOHN and ISAAC BROWN, of Leonardsville, in the county of Madison and State of New York, have invented a new and Improved Street-Sweeping Machine; and we do hereby declare that the following is a full, clear, and exact description of the same, reference being had to the annexed drawings, making a part of this specification, in which—

Figure 1, is a longitudinal vertical section of our improvement, (x), (x), Fig. 2, showing the plane of section. Fig. 2, is a plan or top view of ditto. Fig. 3, is a detached view of one of the clutches by which the working parts are thrown in and out of gear with the driving wheels.

Similar letters of reference indicate corresponding parts in the several figures.

20 The nature of our invention consists,—
1st. In the employment or use of a reciprocating broom constructed and arranged as will be presently shown and described.

25 2nd. Our invention consists in the employment or use of an endless apron for conveying the dust swept upon it by the broom from underneath the machine and depositing it in windrows in the street.

30 3rd. Our invention consists in the combination of the endless apron and broom.

4th. Our invention consists in supporting the back part of the machine by a swivel wheel which is connected by a bar to the 35 back end of the draft pole for the purpose of allowing the machine to turn readily, as will be hereafter shown and described.

5th. Our invention consists in the employment or use of gearing so arranged that 40 the working parts of the machine may be readily thrown out of gear with the driving wheels.

To enable others skilled in the art to fully understand and construct our invention, we 45 will proceed to describe it.

A, represents a rectangular framing in which a transverse shaft B, is permanently secured, said shaft B, being at the front end of the framing. On the shaft B, there are 50 placed loosely, two driving wheels C, C, which have geared rims D, D, attached to their inner sides.

E, is a shaft which works in bearings at the front part of the framing A. This 55 shaft E, has two pinions F, F, placed loosely upon it, which pinions gear into

the rims D, D. On the shaft E, there are placed loosely two ratchets G, G, which are made to gear with the pinions F, F, or disconnect therefrom when desired by inclined flanches a, on the ends of a sliding plate H, which is operated by a lever I, said flanches fitting in grooves a', in the collars (b), of the ratchets, see Figs. 2 and 3. The inner ends of the collars b, of the ratchets have projections (c), upon them, which fit in recesses in hubs or bosses d, attached permanently to the shaft E.

From the above description it will be seen, that, when the lever I, is so moved that the flanches a, will throw the ratchets G, G, in gear with the pinions F, F, the driving wheels C, C, will rotate the shaft E, but when the ratchets are thrown out from the pinions F, F, the driving wheels and pinions will rotate without affecting the shaft, E, which will remain stationary. The ratchets G, G, will rotate the shaft E, in one direction only as when the machine is moved backward the pinions will slip over the teeth of the ratchets which are kept toward the pinions by spiral springs (e), placed between the collars (b), of the ratchets and the hubs or bosses (d), see Fig. 3. To the back part of the framing A, there is attached a swivel wheel J, the shaft K, of which has a horizontal arm, (f), attached to it.

L, is the pole attached to the front end of the framing A. The back part of the pole is attached to an upright shaft M, which has a horizontal arm g attached to it. To the outer end of the arm (g), and to the outer end of the arm f, a bar N, is attached. By connecting the bar N, with the swivel wheel J, and draft pole as shown the wheel J, will be turned according as the draft pole is turned for the team in turning will of course turn the draft pole and the wheel J, will turn simultaneously with it and throw around the back end of the machine in the proper direction.

To each end of the shaft E, there is attached a crank O, to which, pitmen P, P, are connected. The outer ends of the pitmen P, P, are attached to plates (h), (h), which are connected to the ends of a shaft Q each end of which has a wheel R, upon it. These wheels work between guides S, S, attached to the inner sides of the framing A. The plates (h), (h), are perforated with holes and a bar T, is placed between

the plates, the ends of the bar fitting in the holes in the plates. The back side of the bar has a projection U, attached to it, in which a slot (i), is made and through which 5 slot a set screw j, passes into an arm (k), attached to the shaft Q, see Fig. 1.

On the bar T, there are placed slides V, which are secured at proper points upon the bar T by set screws (l). The lower ends 10 of the bar T, have sockets (m), attached to them by joints (n).

W, represents brooms or brushes, the handles (o) of which pass through the sockets (m) and are secured therein by set screws 15 (p) see Fig. 1. The upper ends of the sockets (m) have springs u, bearing against them said springs being attached to the slides V. X, represents an endless apron which works over a transverse platform Y, 20 attached by swinging arms (q), (q), to the framing A, the apron being near the surface of the ground, see Fig. 1. The apron X, is driven by a belt or rope (r) which passes around a pulley (s) at the end of one 25 of the rollers of the apron around guide pulleys (t) and around one of the hubs or bosses (d) on the shaft E, a flap X', is attached to the outer edge of the platform Y.

As the machine is drawn along the shaft 30 E, will rotate when the lever I, is moved so as to throw the ratchets G, G in gear with the pinions F, F, and the endless apron X, is operated by the belt or rope (r), and the bar T, and brooms or brushes W, are moved 35 back and forth by the pitmen P, P, the brooms or brushes being elevated during their backward movement in consequence of the bar T, being attached to the pitmen a certain distance from their points of attachment to the shaft Q and the elevation 40 of the bar and brooms may be increased or diminished by adjusting the bar T, nearer to or farther from the shaft Q. The brooms or brushes as they move toward the apron 45 X sweep the dirt from the street upon it,

and the apron conveys the dirt to one side of the machine and deposits it in windrows in the street. The jointed sockets (m) and the springs (u) allow each brush to yield or give in case of meeting with obstacles and the brooms may be set at any required angle by means of the set screw (j). 50

The above machine is extremely simple in construction not liable to get out of repair and will operate effectually. 55

Having thus described our invention, what we claim as new and desire to secure by Letters Patent, is,

1. The reciprocating brooms or brushes W, attached to a bar T, which is connected 60 with the pitmen P, P, the above parts being arranged as shown or in an equivalent way.

2. We claim the endless apron X, placed underneath the machine for the purpose of 65 receiving the dirt from the brooms or brushes W, and conveying it from underneath the machine and depositing it in windrows in the street, as described.

3. We claim the combination of the endless apron X and reciprocating brooms or brushes W, arranged as herein shown and described. 70

4. We claim connecting the swivel wheel J, with the back end of the draft pole L, by 75 a bar N, substantially as shown for the purpose specified.

5. We claim placing the driving wheels C, C, and pinions F, F, loosely on their respective shafts and operating the ratchets 80 G, G, by means of the flanged sliding plate H substantially as shown for the purpose of throwing the working parts of the machine in and out of gear with the driving wheels.

M. W. ST. JOHN.
ISAAC BROWN.
